UNITED STATES PATENT OFFICE.

ANTHONY VANDERVELD, OF GRAND RAPIDS, MICHIGAN, ASSIGNOR TO GRAND RAPIDS SHOW-CASE COMPANY, OF GRAND RAPIDS, MICHIGAN, A CORPORATION OF MICHIGAN.

DISPLAY DEVICE.

1,032,969.

Specification of Letters Patent. Patented July 16, 1912.

Application filed February 6, 1911. Serial No. 606,912.

To all whom it may concern:

Be it known that I, ANTHONY VANDERVELD, a citizen of the United States, residing at Grand Rapids, in the county of Kent and 5 State of Michigan, have invented an Improvement in Display Devices, of which the following description, in connection with the accompanying drawings, is a specification, like letters on the drawings representing 10 like parts.

The invention to be hereinafter described relates to devices for displaying goods, such as merchandise and the like, and more particularly to such devices as used in stores 15 for the exhibition of goods for sale.

In such devices it is desirable that the goods or merchandise be normally maintained in a case or compartment to protect the goods or merchandise from dust or dirt 20 and from handling by unauthorized persons, and at the same time that the goods or merchandise be capable of ready inspection or examination when withdrawn from the case or compartment. It has heretofore been 25 proposed to provide a rotatable support for the goods or merchandise which shall be movable to and from a position within the case or compartment, and when being so bodily moved shall be prevented from rotative movement so that the support for the 30 goods or "rack," as it may be termed, shall not injure the case or compartment, and shall be freed to rotative movement when at the front of the case or compartment. It 35 has also been proposed to provide means, so that when the "rack" is in front position and rotated, the rack cannot be moved back into the case. An instance of the above is presented in the application of Oscar L. 40 Smith, Serial No. 524,451, filed October 29, 1909.

The aims and purposes of the present invention are to provide a display device of simple construction and wherein the rotatable rack shall be sustained in an efficient 45 manner as it is bodily moved with relation to the case or compartment, and wherein improved means is provided for locking the rotatable rack from rotative movement 50 while being moved to and from a position within the case or compartment and is freed to rotative movement when moved to front position, and wherein, when in front position, the rack is locked from bodily movement 55 into the case. These aims and pur-

poses of the invention, and others incident to the invention, will best be made clear from the following.

In the drawings:—Figure 1 is a front elevation of a display device embodying the present invention, parts being broken away; Fig. 2 is a section on the line 2—2, Fig. 1; Fig. 3 is a section on the line 3—3, Fig. 1, with the case omitted, showing the carriage and track frame beneath the floor of the case 65 with the carriage in rear position; Fig. 4 is a view similar to Fig. 3 with some of the parts omitted to more clearly show the action of the locking device when the carriage is moved to front position; and Fig. 5 is a 70 plan view of the track frame, the rack, and carriage, the inclosing case being omitted.

The inclosing case or compartment 1 may be of any desired type, and is herein shown as comprising a top 2, and sides 3, and back 75 4, which may be formed of glass, the front of the case being closed by suitable doors, not shown. The bottom of the case may be formed of a base piece 5, between which and the floor 6 of the case the supporting car- 80 riage may conveniently be located.

Suitably secured to the case between the base piece 5 and floor 6 is the track frame preferably comprising the side members 7, 7, Figs. 1, 3, 4 and 5, extending from front 85 to rear of the case. This track frame forms a suitable guide for the carriage A, Figs. 1 and 2, and may be of any convenient type, but as herein shown consists of the side members 7, 7 formed of metal having flanged 90 upper and lower portions 8, 9, Fig. 1, between which run the rollers 10 connected by suitable axles 11 on which rest the bearing portions 12 of the carriage A, suitable stops 13 on the carriage serving to maintain the 95 rolling supports for the carriage in proper relation thereto. The front and rear portions of the side members 7, 7 may be connected by cross pieces 14, 14.

It will be noted that the carriage has a 100 rearward extending portion 15 and that the rollers 10 are widely separated, the effect being that the carriage is more effectively supported and prevented from tipping as it is moved toward and from its position within 105 the case. To further prevent any tilting movement, the carriage may have secured thereto the rollers 16, 17, which bear upon the under surface of the upper flange 8 of the track frame, Figs. 2, 3 and 4. 110

One of the purposes of the present invention is to support the rotatable rack in a manner to secure ease of rotative movement and at the same time effectively prevent the strain upon the rack, especially as it is moved to and from its normal position within the case. As one means to this end, the invention contemplates sustaining the rack carrying or upright shaft upon an anti-friction bearing and providing means at the base and near the top of the shaft to securely brace the same while providing efficient bearing supports.

In the particular form of the invention shown, the carriage has rising thereupon the pedestal portion 18 which is either formed integral with the carriage, or, as shown in the drawings, may be constructed separately therefrom and secured thereto as by the bolts 19, see Figs. 1 and 3. It will be evident that the principal strain upon the carriage, and that which is most effectively exercised by the rack as it is being moved to and from its position within the case, is in a direction longitudinally of the carriage, and to meet this condition the pedestal 18 has front and rear extending portions 20, as indicated in Figs. 1, 2 and 3, preferably formed as webs connecting the base portion of the pedestal with its bearing portion 21. It will be noted from Fig. 1 that the bearing portions 20 extend through a suitable slot 22 in the floor 6 of the case and that above the floor of the case the bearing 21 is enlarged. Secured within the bearing 21 and extending upward therefrom is the sleeve 23 having a bearing portion 24 at its upper end which may be of any usual or desired character.

Passing through the sleeve 23 and the upper and lower bearing portions 21 and 24 is the rack carrying or upright shaft 25 which, at its upper portion, may have secured thereto the hub 26 from which project the spider arms 27 carrying suitable rods or other devices 28 for supporting garments or other goods to be displayed. Obviously, the form, character and shape of the rack is not material to the present invention, and that shown and described is for the purpose of making clear the characteristic features of the invention without limiting the same thereto.

Below the end of the rack carrying shaft 25, the carriage has a supporting piece 29 which may be of hardened metal such as steel and on which is sustained a hardened pin 30 secured to the lower end of the shaft 25, said hardened block and hardened pin thus acting as an anti-friction bearing for sustaining the weight of the rack and shaft and permitting the rack to be readily and easily rotated.

From the construction thus far described, it will be apparent that as the rack is

moved to and from its position within the case or compartment, the widely separated bearing portions of the carriage on the track frame and the correspondingly widely separated bearing portions for the rack carrying shaft 25 and the longitudinally extending web portions 20 of the pedestal will effectively prevent any tilting or tipping movement of the rack and will maintain it in normal vertical sliding relation with the case or compartment. It will also be noted that by making the web portions 20 of the pedestal extending in a longitudinal direction, the tendency to front and rear rocking movement will effectively be obviated while at the same time the slot in the floor of the case can be made correspondingly small or narrow. It will likewise be noted that the hardened pin and block, one on the carriage and the other on the end of the shaft 25, will afford a convenient and simple, durable and effective anti-friction device for taking the end thrust of the shaft and its load and yet permitting the shaft to be readily rotated when free to said movement.

It is desirable in this class of devices, when the rack is moved to its position within the case that it be prevented from rotating on its axis, because said rotative movement will, under such conditions, injure or break the case; on the other hand it is desirable that the rack be freed to rotative movement when it reaches its front position with respect to the case, and that when so rotated it be locked or prevented from being bodily moved into the case. The present invention affords means to accomplish the ends stated and, as one convenient form of such means, the following is shown and described. Secured to the lower portion of the shaft 25 is a disk 31, Figs. 2 and 4, said disk being provided with diametrically opposite recesses 32 which are so related to the arms 28 of the rack that when said recesses are in the position indicated by Figs. 3 and 4, the rack will be properly related to the case to enable the rack to be moved into and out of the case without liability of injury to the case by contact with the rack. Pivotaly mounted at 33 on the carriage and adjacent the disk 31 is a lever 34, for identification to be known as the locking lever. This lever carries a roll 35 suitably supported thereon as by a bracket or casting 36, as shown, said roll 35 being adapted to engage either of the rollers 32, as will hereinafter more fully appear. Also secured to the carriage A at 37, Figs. 3 and 4, is a lever 38 which, for identification, may be known as the lever catch, and connecting the lever 38 and one arm of the lever 34 is a spring 39, the normal tendency of which is to move the locking lever contra-clockwise, viewing Figs.

3 and 4, to cause the roll 35 to engage a recess 32, should such recess be opposite the roll, and normally tending also to move the lever catch 38 clockwise for a purpose that 5 will hereinafter fully appear. One end of the lever catch 38 is provided with a shouldered portion 40 which, at certain times, is adapted to be engaged by a lip 41 on the locking lever 34, the construction being such 10 that when the lip 41 engages the shouldered portion 40, the locking lever will be locked from movement on its pivot 33, as is shown, for instance, in Fig. 3, but when the lip 41 and shoulder 40 of said respective levers are 15 disengaged, as in Fig. 4, then the locking lever 34 is freed to be moved on its pivot 33, as will be readily apparent from Fig. 4.

Mounted in fixed position and preferably on one of the side members 7 of the track frame is a trip 42 having two finger portions 43, 44 of unequal length and extending, as indicated in Figs. 3, 4 and 5, toward the path of movement of the carriage. The trip 42 is disposed in the path 20 of movement of the end 45 of the lever catch 38, so that as the carriage is moved from its rear position, as indicated in Fig. 3, to its front position, as indicated in Fig. 4, the end 45 of the lever catch will pass by the 25 projection 43 of the trip but will engage the longer projection 44 of the trip, with the result that the end 45 of the lever catch will be moved contra-clockwise, thereby freeing the shoulder portion 40 thereof from 30 engagement with the part 41 of the locking lever, the parts then being in position as indicated in Fig. 4.

With the parts in position as indicated in Fig. 4, due to bearing the carriage bodily 40 from its position within the case to the front of the case, it will be noted that the rack may be rotated upon its vertical axis by a slight pull tending to such rotative movement, whereby the roll 35 of the locking 45 lever is forced out of the notch 32 against the action of the spring 39 and the rack can be moved rotatively backward and forward to any degree. When, however, a notch 32 passes the roll, the roll will drop into the 50 notch and the parts will assume position, as indicated in Fig. 4, the rack being then properly disposed with relation to the case to be moved thereinto without danger of injuring the case.

55 When the rack is rotated from the position indicated in Fig. 4, and the roll 35 is forced out of the notch 32, the end portion 41 of the locking lever passes over and beyond the shouldered portion 40 of the lever catch, so that said lever catch cannot be moved clockwise, and since the end 45 of the lever catch is maintained between the projections 43, 44 of the trip at this time, it follows that the rack cannot be moved toward the rear position within the case.

Thus when the rack is rotated so that the arms thereof would be liable to injure the case, if moved bodily with reference thereto, the rack is locked from such bodily movement, but when the rack is located with respect to the case so that such injury would not be liable, then the rack is locked from rotative movement but free to bodily movement toward or from its position within the case. 75

As the rack is moved toward the front of the case from the position indicated by Fig. 3 and that of Fig. 4, it is desirable that its forward movement be checked at the proper point and to this end suitable buffers 46 are 80 provided as will be clear from Figs. 3 and 4.

While the details of the locking device and catch and the relation of the catch to the trip are preferred as a good and convenient form of the invention, it is to be understood that these parts may be differently disposed and combined in different relations, the purpose being that as the carriage and rack move to and from the position within the case, the rack be locked from 90 rotative movement, and that when the carriage and rack are moved to the front position, the rack be free to rotative movement, and that when so freed and rotated, the rack and carriage be locked from bodily movement into the case. 95

What is claimed is:

1. In a store display device, the combination of a case or compartment having a floor provided with a slot, a carriage movable to 100 and from a position within the case or compartment below the floor, a pedestal rising from the carriage and having web portions extending longitudinally of and within said slot, a bearing supported by the web portion 105 above the slot in the floor and of greater diameter than the width of said slot, a rotatable rack, and a support for said rack mounted in said bearing. 110

2. In a store display device, the combination of a case having a floor provided with a narrow slot, a rotatable rack, a movable support for said rack below the floor, a web rising from said movable support and extending through the slot in the floor, a bearing of larger cross sectional dimension than the slot sustained by the web above the floor, a rack support mounted in said enlarged bearing above the floor and having its lower end extending below the narrow slot in the floor, and a thrust bearing between the movable support below the floor and the rack support. 115

3. In a store display device, the combination of a case having a floor provided with a slot, a carriage movable below the floor, a web rising from the carriage and sustaining a bearing above the slot in the floor, a rack supporting shaft having lateral 125 support in said bearing above the slot and 130

extending downward beyond the horizontal plane of said slot, said shaft having a reduced diameter in the plane of and to move in said slot, and a thrust bearing between the shaft and carriage below the horizontal plane of the slot.

4. In a display device, the combination of a case or compartment, a carriage movable to and from a position within the case, 10 a rotatable rack mounted to move with said carriage, a locking member rotatable with the rack, a locking lever pivotally mounted on the carriage and adapted to engage said rotatable locking member, and a trip for 15 unlocking the rack.

5. In a display device, the combination of a case, a carriage movable to and from a position within the case, a rotatable rack having a locking member, a locking lever 20 mounted on the carriage, a spring for turning said lever into locking engagement with the said locking member, and a lever catch for locking the locking lever in such engaged position.

25 6. In a display device, the combination of a case, a carriage movable to and from a position within the case, a rotatable rack having a locking member, a locking lever mounted on the carriage, a spring for turning 30 said lever into locking engagement with the said locking member, a lever catch for locking said locking lever in such engaged position, and a trip for said catch.

7. In a display device, the combination 35 of a case, a carriage movable to and from a position within the case, a rotatable rack mounted for movement with the carriage, a locking member connected to said rack, a locking lever pivotally mounted on the carriage and adapted to engage said locking member, and a lever catch for engaging the 40 end of the locking lever and locking it from disengagement from said member.

8. In a display device, the combination 45 of a case, a carriage movable to and from a position within the case, a rotatable rack mounted for movement with the carriage, a locking member connected to said rack, a

locking lever pivotally mounted on the carriage and adapted to engage said locking member, a lever catch for engaging the end of the locking lever and locking it from disengagement from said member, and a trip for freeing the lever catch and locking lever.

9. In a display device, the combination 55 of a case, a rotatable rack for supporting goods movable to and from a position within the case, a lock to prevent rotative movement of the rack, a catch to render the lock effective as the rack is moved to or 60 from a position within the case, and means to trip the catch and render the lock ineffective when the rack is moved to a position at the front of the case, said tripping means having a device acting through the 65 part moved by the tripping means to prevent movement of the rack into the case.

10. In a display device, the combination 70 of a case, a rotatable rack movable to and from a position within the case and having a locking member, a locking lever to engage the locking member, a catch for co-operating with and locking the locking lever to prevent rotative movement of the rack as it is 75 moved to or from position within the case, and means to trip the catch and free the locking lever from the catch as the rack reaches front position.

11. In a display device, the combination 80 of a case, a rotatable rack movable to and from a position within the case and having a locking disk, a locking lever to engage the locking disk, a catch for co-operating with and, for locking the locking lever to prevent rotative movement of the rack as it is 85 moved to or from position within the case, and means to trip the catch and lock the rack in front position as the rack reaches said position.

In testimony whereof, I have signed my 90 name to this specification, in the presence of two subscribing witnesses.

ANTHONY VANDERVELD.
